UNITED STATES PATENT OFFICE.

LERoy H. PERRY, OF GARDENA, CALIFORNIA.

WELL-CASING PROTECTOR.

Application filed June 25, 1924. Serial No. 722,344.

To all whom it may concern:

Be it known that I, LEROY H. PERRY, a citizen of the United States, residing at Gardena, in the county of Los Angeles and 5 State of California, have invented a new and useful Well-Casing Protector, of which a specification is set forth below.

In this specification, and the accompanying drawing, I shall describe and show a 10 preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to the art of deep 20 well drilling and particularly to means for preventing rotary tool strings from rubbing against the casing walls and thereby causing damage. It is well known that the casing, or water string, is frequently worn 25 through in this manner and that, especially when a hole has been made in the casing far below the surface of the ground, it is a very expensive matter to repair such damage.

My principal objects in the invention are; 30 first, to provide means at regularly spaced intervals throughout the length of the revolving tool string for keeping it out of direct contact with the casing; second, to prevent abrasion of the walls of the casing by the tool string by interposing at the said 35 intervals an antifriction bearing or, if preferred, a wearing surface to take the abrasion that the casing would otherwise be subjected to; and, third, to accomplish the 40 above by means of a relatively simple and inexpensive device that is well adapted for its intended purpose.

My objects are attained in the manner 45 illustrated in the accompanying drawings, in which—

Figure 1 is a longitudinal central section 50 of a deep well with a preferred embodiment of my invention therein, the latter being shown broken and partly in longitudinal central section;

Figure 2 is a cross section of the above 55 construction, taken on the line 2—2 of Figure 1;

Figure 3 is a dis-assembled and broken 60 view in elevation of a tool string with my casing protector thereon;

Figure 4 is a view similar to Figure 1 indicating the manner in which a friction shoe may be added to my device;

Figure 5 is an elevation on a reduced 60 scale of the working parts shown in Figure 4;

Figure 6 is a central longitudinal section 65 of a well with a modified type of my invention therein; and

Figure 7 is a cross section taken on the line 7—7 of Figure 6.

Similar reference numerals refer to similar parts throughout the several views.

In the drawings the casing of a deep well 70 is indicated at 8. Within this casing is a rotary tool string 9, coupled at intervals as by tool joints 10 in the manner common to the art. My protector is applied to the tool string as it is being made up above ground, 75 and ordinarily just above alternate tool joints.

The invention comprises a sleeve 11 bored 80 to fit the outside of the tool string. This sleeve has a flange 12 at the bottom, and a taper thread 13 at the top. The top end is also provided with a plurality of longitudinal kerfs 14 so that it may be contracted by means of nut 15 to tightly grip the tool string.

Surrounding the sleeve and floating between flange 12 and nut 15, is a collar 16 having an outside diameter only slightly smaller than the bore of the casing. The inside diameter of the collar is considerably 90 larger than the body of sleeve 11. Ordinarily both the collar and the sleeve are hardened.

In the usually preferred form of my invention, illustrated in Figures 1 to 5 inclusive, I employ a relatively large number of hardened small rolls 17 in the annular space between the sleeve and the collar. This construction then constitutes a roller bearing serving to keep the rotary tool 95 string substantially central in the well and preventing the string from abrading the casing.

A friction shoe 18 of rubber or similar 105 material may be applied to this type of casing protector in the manner illustrated in Figures 4 and 5. For this purpose the central portion of the outer surface of collar 16 is turned down, leaving a small flange 19 at each end. The shoe may be split 110 angularly as shown at 20 if the material is not sufficiently resilient to be stretched over

flanges 19 when being mounted upon the collar.

In the modified type of my invention shown in Figures 6 and 7 I dispense with 5 the rollers entirely. In this case the outer surface of sleeve 11 is permitted to rub against the inner surface of collar 16. The wear that the well casing would otherwise be subjected to is thus transferred to the 10 collar and sleeve since, by reason of the difference in diameters, there is much less tendency for the collar to slide against the inner wall of the casing than there is for the sleeve to slide against the inner wall 15 of the collar. In this construction the sleeve is made harder than the collar so that it is chiefly the latter that wears. The collars are made of relatively inexpensive material and are cheaply renewed when worn out. 20 A friction shoe similar to 18 may be added to the outside of the collar as in this case as well as in the case of the type of my invention previously described. Such a shoe will absolutely prevent any abrasion of the 25 well casing and will insure that such wear as occurs will take place on the collar and sleeve.

The nut 15 is ordinarily designed for use with a spanner wrench, and one or more 30 peripheral holes 21 are provided for that purpose.

The construction and method of using my invention will be clearly apparent from the foregoing description and need not be 35 further elucidated. I desire, however, to call attention to the simplicity and relative cheapness of the device, and particularly to the great saving in repairs to casings its use will bring about. This feature will 40 be readily appreciated by those familiar with the drilling art.

I claim as my invention:

1. A well casing protector comprising; a flanged sleeve having a longitudinally kerfed 45 taper-threaded end adapted for gripping a tool string; a nut engaging said thread adapted for contracting said end; and a collar surrounding said sleeve between the flange and nut adapted to contact with a well casing when lateral pressure is exerted by the tool string.

2. A well casing protector comprising; a flanged sleeve having a longitudinally kerfed taper-threaded end adapted for grip-

ping a tool string; a nut engaging said 55 thread adapted for contracting said end; and a floating collar surrounding said sleeve between the flange and nut adapted to contact with a well casing to protect it from abrasion when lateral pressure is exerted by the tool string.

3. A well casing protector comprising; a flanged sleeve having a longitudinally kerfed taper-threaded end adapted for gripping a tool string; a nut engaging said 65 thread adapted for contracting said end; and a floating collar surrounding said sleeve between the flange and nut adapted to contact with a well casing to protect it from abrasion when lateral pressure is exerted by 70 the tool string; the periphery of said collar being of yieldable friction material.

4. A well casing protector comprising; a flanged sleeve having a longitudinally kerfed taper-threaded end adapted for gripping 75 a tool string; a nut engaging said thread adapted for contracting said end; a floating collar surrounding said sleeve between the flange and nut; and rollers between said sleeve and collar.

5. A well casing protector comprising; a flanged sleeve having means for gripping a tool string; a floating collar surrounding said sleeve; and rollers between said collar and said sleeve; said collar being adapted 85 to contact with a well casing to protect it from abrasion when lateral pressure is exerted by the tool string.

6. A well casing protector comprising; a flanged sleeve having a longitudinally kerfed taper-threaded end adapted for gripping a tool string; a nut engaging said 90 thread adapted for contracting said end; a floating collar surrounding said sleeve between the flange and nut; and hardened 95 rollers between said sleeve and collar; the periphery of said collar being of yieldable friction material adapted to contact with a well casing to protect it from abrasion when lateral pressure is exerted by the tool string.

7. A well casing protector comprising; a sleeve adapted for gripping a tool string intermediate the tool string joints; and a floating collar surrounding said sleeve; said 105 collar having an outside diameter larger than that of said joints.

LEROY H. PERRY.
